(57) **CLAIM**

The ornamental design for GPS navigation, as shown and described.

DESCRIPTION

FIG. 1 is a perspective view of front, right and top of a GPS navigation showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines showing of the GPS navigation is included for the purpose of illustrating portions of the GPS navigation and forms no part of the claimed design.
